RAIL JOINT

Otto Balcar, Cedar Rapids, Iowa

Application July 23, 1938, Serial No. 220,907

2 Claims. (Cl. 238—218)

This invention relates to rail joints and has particular relation to a means for joining rails in such a manner that the weight on a wheel is transferred from one rail to another by means of an angularly cut rail.

In joining rail ends, allowance must be made for expansion, and the difficulty with most of the devices hitherto proposed, in which angularly cut rail ends are employed, is that the rail ends would 10 override one another under extreme expansion. The rail ends would slide past each other and shear the holding means employed to hold the ends of the rails in alignment.

In accordance with my invention, the rail ends, 15 when the rails are expanded, maintain their alignment and yet are tied together in such manner that the entire joint is one solid unit and the weight of the train is transferred from one rail end to the other without jarring or bumping.

It is, therefore, a general object of my invention to provide, in a rail joint, means for preventing overriding of the ends of the rails.

It is another object of my invention to provide means for locking the rail ends together in such 20 manner that they form one solid unit.

A further object of my invention is to provide a joint plate adapted to make possible the compensation for wear at base and top surfaces without the necessity of removing the joint plates 25 from the rail.

Another object of my invention is to provide means for transferring the load from one rail end to the other without permitting the wheel to drop or pound.

Another object of my invention is to increase the permissible travel of the rail ends in expanding and contracting without increasing the gap.

Still another object of my invention is to provide a rail joint which may utilize joint bars of usual construction with the addition of parts constructed according to my invention whereby a change may be made, from the usual type of construction, to a device constructed according to my invention, without discarding the old equipment.

A still further object of my invention is to provide a device such that rail joints may be made in the field with no more than the usual equipment.

Other and further features and objects of the invention will be more apparent to those skilled in the art upon a consideration of the accompanying drawings and following specification, wherein is disclosed an exemplary embodiment of 55 the invention, with the understanding, however,

that such changes may be made therein as fall within the scope of the appended claims, without departing from the spirit of the invention.

In said drawings:

Figure 1 is a view in perspective of a rail joint constructed according to one embodiment of my invention.

Figure 2 is a view in perspective of the rail ends, prepared according to my invention, as they appear before being joined together.

Figure 3 is a view in transverse section showing a rail joint, constructed according to my invention, at it appears when assembled.

Figure 4 is a view in perspective of the base plate of the device shown in the Figures 1 and 3.

Figure 5 is a view in perspective of a joint bar constructed according to one embodiment of my invention.

Figure 6 is a view in perspective of an auxiliary bearing plate constructed according to one embodiment of my invention, and

Figure 7 is a fragmentary view in section showing a means of engaging the rail ends without running the bolt through the joint bars.

Referring now to the drawings and more particularly to Figures 1 and 2; in practicing my invention I preferably cut the rail ends of a bias or angle, as illustrated in Figures 1 and 2. I have found that an angle of 45 degrees is about right for the purpose. In cutting the rails on an angle, several purposes are accomplished. The lap joint accomplishes transfer of the load from one rail to another without dropping the wheel or jarring, inasmuch as both rail ends carry the weight of the wheel and the load at the same time until the transfer is accomplished, the transfer from one to the other being gradual rather than abrupt. Further, the allowance for expansion of the rail is increased without using any wider gap between the rail ends. Furthermore, the abutting area of the rail ends is increased. The rail ends are indicated at 10 and 11.

I may also serrate or groove the rail ends, as indicated in Figures 1 and 2, so as to prevent the rail from slipping sidewise, one over the other, or overriding one another, as it may be termed. These serrations, indicated at 12, may be vertical as shown, or may be horizontal or curved, but the best results are secured with the vertical serrations. The serrations are so arranged that when the rail ends are abutted one against the other, as in hot weather, the projections of the serrations of one rail end project into the recesses of the other serrations of the other rail end.

In connecting the rail ends, joint bars 13 and 14 are utilized in much the same manner as in the usual construction, the only difference being that a fifth hole through the bars is provided 5 at the center thereof, as indicated at 16. The bars ordinarily used may be converted by drilling an additional hole at the midpoint of the bar, or the usual bar may be employed and a plug or spool placed in the opening 16 between 10 the rail ends as shown in Figure 7.

These joint bars, in accordance with the usual 15 practice, have bulbous upper edges 13a and 14a which bear against the under side of the ball of the rail and have flanged lower edges indicated 15 at 13b and 14b which bear against the base of the rail.

In accordance with one embodiment of my 20 invention, however, I may curve the web of the joint bar as indicated so that when wear of the flanges occurs, the web of the bar may be heated and the bolts drawn up to spread the bar to compensate for wear.

The ends of the rails are pierced by holes 15 and these holes pass directly through the web 25 of the rails and are centrally located in the ends of the rails in the center of the abutting walls of the webs. Bolts or rivets passed through these holes will assist in preventing the rail ends from overriding one another.

30 My invention contemplates forming a stiff rail joint which is as stiff or has even greater stiffness than the rail itself, and to this end I provide an auxiliary bearing plate or side plate 17 formed along the central, longitudinal, inner 35 face thereof, to bear against the outside face of the outside joint bar 13. The upper edge 17a preferably extends upwardly beside the outer face of the ball of the rail so that the upper edge thereof is substantially parallel with the 40 top surface of the rail. This edge is thus so positioned that the outer edge of the wheel 18 will run on this auxiliary bearing plate in crossing over from one rail end to the other.

I preferably bevel the outer upper edge of 45 this auxiliary bearing plate, as indicated at 17b, at both ends thereof, so that, even if the bearing plate should accidentally be placed on the inside of the rail, it will not derail a train. The upper edge of the side plate 17 is preferably slightly 50 beveled downwardly and outwardly, as indicated at 17c, as the main portion of the tread of the wheel 18 may become worn leaving a slight rim at the portion 18a. The lower edge 17d of the side plate 17 is preferably beveled to be received 55 in the flange 19a of the base plate 19. It is also provided with a groove, indicated at 17e, for receiving the flanges of the joint bar 13 and the base of the rail 11.

The inner edge of the base plate 19 is provided 60 with an upwardly and inwardly extending flange 19b adapted to extend up and over the edge of the base of the rail and the lower flange of the inner joint bar 14.

The clearances of the various parts of the 65 device are so arranged and chosen that when the base 19 is laid and the rail ends joined by means of the joint bars, the auxiliary bearing plate may be driven parallel to the rail between the outer edges of the flange or base of the 70 rail and the flange 19a of the base plate 19 to wedge the entire assembly into one solid joint. When the auxiliary bearing plate has been driven to its proper position, it is engaged in this position by driving a spike 21 home through the 75 opening 22 in the base plate and through a notch

23 of the auxiliary bearing plate. The bolts 24 are passed through the openings 26 and 27 of the auxiliary plate and through the oval openings 28 of the joint bars and openings 29 and 15 of the rails. The nuts 31 are threaded into 5 place to draw up the assembly of the joint bars and auxiliary plate to wedge these members into substantially one unitary member.

The spike opening 30 is slightly offset with respect to the notch 32 and with regard to the 10 parts of the rail joint. The spike may be placed in this opening 30 and in the notch 32 to hold the auxiliary plate in tightened position. The flange 19a, of the base plate 19, is tapered from point 34a to 36a, and the lower edge of the auxiliary 15 plate 17 is correspondingly tapered from point 34 to 36 so that, as the auxiliary bearing plate is driven from left to right, the joint is tightened up. In tightening the joint after considerable use, the plate 17 is driven slightly further to the 20 right so that the opening 30 and the notch 32 line up and the auxiliary bearing plate is then locked in place by means of a spike through the opening 30 and notch 32.

My provision for a joint bar having a slight 25 vertical curve throughout its length as illustrated at 13c of Figure 5 makes it possible to compensate for wear along the upper and lower edges without the necessity of taking the joint apart. This is accomplished by heating the joint bar 30 with a torch throughout its length and along the curved portion. This heating makes it possible to spread the bar vertically by drawing up the nuts on the joint bolts.

In converting ordinary equipment over to 35 devices constructed according to my invention, I may utilize spool-like members 41 through the abutting ends of the webs, instead of the bolts 24 through the center opening and it will be unnecessary to provide the fifth hole 16 in the joint 40 bars or side bars 13 and 14.

Many advantages flow from the use of devices 45 constructed according to my invention. It substantially eliminates jarring of the rail ends and the depression at the rail joints resulting therefrom, thus making a material reduction in the cost of maintaining a roadbed to an even substantial surface, largely eliminating the cost of maintaining joints in safe, serviceable condition, both as to labor and replacement charges. These 50 devices greatly reduce damage to the rolling stock and bridge structures resulting from excessive vibration and shock, and make possible increase in speed of trains without diminishing the factor of safety. They materially extend the 55 useful life of the rails. Some of the secondary advantages are that they make possible the use of rails of greater length which lengths are now restricted by practical limits of space allowed between rail ends for heat expansion, and thus reduce the number of joint fastenings in the track. The expansion can safely be taken care of by the gap in the diagonal rail joints supplemented 60 by the auxiliary bearing surface of the side plate, and placing the expansion space at a 45 degree 65 angle with the rail increases the free space for longitudinal travel of the rail end by nearly 50%. It eliminates the use of short rails at curves and at bridge abutments, now required to maintain an even break or stagger of joints in curves, or 70 where it is necessary to avoid locating a joint too close to an abutment.

Although I have described a specific embodiment of my invention, it is apparent that modifications thereof may be made by those skilled 75

in the art. Such modifications may be made without departing from the spirit and scope of my invention as set forth in the appended claims.

I claim as my invention:

5. 1. A rail joint including a base plate having two shoulders, joint bars having flanges extending to the edge of the rail base on each side of the abutting ends of the rails, and an auxiliary plate extending from the top surface of the head 10 of the rail fitting against a joint bar on one side of the rail, the base plate having a shoulder at one side thereof having a lip to fit over the bottom of one joint bar and having another longitudinal undercut shoulder positioned laterally of 15 the rails and joint bar with two openings therein, the auxiliary plate being flared at the bottom to form a wedge fit between said undercut shoulder of the base plate and the bottom vertical edge of the joint bar, said auxiliary plate being notched

at two points, one of said notches being offset in relation to a corresponding opening in the undercut shoulder of the base plate.

2. In a rail joint, a joint bar having a flange extending to the edge of the rail base, an auxiliary plate at the side of the rail and extending from the top surface of the head of the rail to a horizontal surface on the flange of the joint bar, a flat base plate for supporting the auxiliary plate and rails, said base plate having a longitudinal undercut shoulder positioned laterally of the rails and joint bar, the lower edge of the auxiliary plate being flared to form a wedged fit between said undercut shoulder of the base plate and the bottom vertical edge of the joint bar, and means for subsequently adjusting said auxiliary plate to tighten the assembly.

OTTO BALCAR.
